DESIGN FOR A NECKTIE OR SIMILAR ARTICLE

Rodney Ettman, Woodmere, N. Y.

Application July 12, 1945, Serial No. 120,658

Term of patent 3½ years

(Cl. D3—16)

To all whom it may concern:

Be it known that I, Rodney Ettman, a citizen of the United States and a resident of Woodmere, Nassau County, in the State of New York, have invented a new, original, and ornamental Design for Necktie or Similar Article, of which the following is a specification, reference being had to the accompanying drawing forming a part hereof, in which the figure is a plan view of the main portion of a necktie or similar article, showing my new design, the rest of the necktie being of conventional outline, and the reverse thereof being undecorated.

I claim:

The ornamental design for a necktie or similar article, as shown and described.

RODNEY ETTMAN.
